DESIGN FOR A BIB

Louis Grassi, Los Angeles, Calif.

Application February 25, 1947, Serial No. 137,169

Term of patent 7 years

(CL. D3—26)

To all whom it may concern:

Be it known that I, Louis Grassi, a citizen of Italy, residing at Los Angeles, in the county of Los Angeles and State of California, have invented a new, original, and ornamental Design for a Bib, of which the following is a specification, reference being had to the accompanying drawing, forming part thereof.

In the drawing

Fig. 1 is a perspective view of the bib, showing my new design, and

Fig. 2 is a vertical section through the bib, substantially on the line 2—2 of Fig. 1.

I claim:

The ornamental design for a bib, as shown.

LOUIS GRASSI.
